Primary Examiner—T. Chase Nelson*Assistant Examiner*—Karen Acker(74) *Attorney, Agent, or Firm*—Christopher R. Pastel; Pastel Law Firm(57) **CLAIM**

The ornamental design for a bonding block for coaxial cable, as shown and described.

DESCRIPTION

FIG. 1 is a front perspective view of my new design of the bonding block for coaxial cable of the present invention;

FIG. 2 is a rear perspective view thereof;

FIG. 3 is a front elevation view thereof;

FIG. 4 is a rear elevation view thereof;

FIG. 5 is a top view thereof;

FIG. 6 is a bottom view thereof;

FIG. 7 is a right side elevation view thereof; and,

FIG. 8 is a left side elevation view thereof.
